PRESSING PAD

Clarence John Crary, Chicago, Ill., assignor to
George Beary, Chicago, Ill.

Application May 24, 1938, Serial No. 209,669

4 Claims. (Cl. 29—148)

This invention relates to pressing pads of the type employed in pressing machines employed in the laundering, tailoring and cloth working industries.

5 A particular object of the invention is to provide a pressing pad so constructed that it will stand up for a long period under constant machine pressures as employed in pressing machines in present day use. The machines are equipped with pressure rendering means that exceed the pressure possible to be exerted by the human operator of a pressing machine and the result of these high pressures applied continuously will soon break down a pad that is not constructed especially to withstand them.

10 It is an important object of the invention therefore, to so construct the pad that it will stand up under pressure for a reasonable length of time, will be subjected to high pressure during manufacture so that the strands of the material employed in making the pad will not be further compressed by the pressing machine, and the pad so constructed that it is heavier along its longitudinal center and stronger through its mid-portion than pads in present day use.

15 A further object of the invention is to construct the entire pad out of three pads that are made up individually and each subjected to pressure and thereafter combined with each other under pressure and wrapping to resist the pressure encountered in the pressing machines. I have found that by employing steel wool in ribbon form, and winding the same laterally to form the central or inner pad, that better results are obtained due to the fact that the ribbons are on edge and wound closely to give a solid, yet yielding effect to the pad which cushions and does not break down readily.

20 My process contemplates a series of steps which includes the laying of steel wool in strand form in a die the shape of a pad to be made so that the strands extend the length of the pad. The mass is then subject to pressure and two pads are so made, which are called outer or crown pads. The 25 crown pads have disposed between them a pad made by laying the ribbon strand of steel laterally on edge and back and forth to fill the die, and then piling or wrapping the strand lengthwise therearound to bring the center of the pad higher, the combination of three pads being then united under pressure to complete the pad construction which may be placed in a fabric covering.

25 With these and other objects in view, my invention comprises the method of construction and article of manufacture as hereinafter described

and particularly illustrated in the accompanying drawing, in which:

Figure 1 is a plan view illustrating the first step of the invention and formation of one of the crown or outer pads.

Figure 2 is a view similar to Figure 1 and shows the method of constructing the other crown pad which is the same as illustrated in Figure 1.

Figure 3 is a view showing the two steps of construction employed in making the center pad.

Figure 4 is a view showing the finished pad and part of the fabric cover used therewith.

Figure 5 is a view in side elevation showing the three pads in the final formation ready to be used in the pressing machine.

Figure 6 is a view in perspective of a ribbon strand of steel wool showing how it appears commercially and as used in the construction of the center pad.

Figure 7 is a transverse section of either of the 20 pads illustrated in Figures 1 and 2 and showing in diagram the appearance of the pad before being subjected to pressure.

Figure 8 is a view similar to Figure 7 showing the appearance of the central or intermediate 25 pad as illustrated in Figure 3, and

Figure 9 is a view in cross section through the finished pad showing the three layers or individual pads united in one.

Referring to the drawing in detail, 10 indicates a ribbon of steel wool as manufactured and consisting of many strands of the wool, the ribbon coming in various lengths and in itself not material to the invention except as employed in my novel process wherein it is laid longitudinally 30 and on edge back and forth as illustrated in Figures 1 and 2 in a suitable die to form a pile, the steel wool being in the form of the ribbon or strand shown in Figure 6 and laid on edge and passed back and forth lengthwise to form the pad mass as at 11. The mass is then compressed under approximately 100 pounds pressure to the square inch to shape it into pad form, the separate pads as shown in Figures 1 and 2 and indicated as outer pads 12 and 13 being similarly 35 formed and referred to as crown or outer pads. In Figure 7, the outline position indicates the thickness of the mass 11 before compression to form the crown pad.

40 In Figure 3, the center pad 17 of a finished pad structure is formed by first laying the ribbon 10 back and forth on edge crosswise of the die form to provide a mass of the steel wool, the strands of which are on edge as at 16 to give a 45 substantial body to the pad. After the pad form

is so constructed, the steel wool in ribbon form 10 is wound lengthwise about the mass in flat position, that is the strand of ribbon wool is flat wound about the mass to form the body of the 5 center pad 17. The strands are so laid that the longitudinal center of the pad is covered with more of the wool than the outer edges thereof and the pad is consequently thicker through its middle than along its outer edges. This laying 10 of the wool to form the thickened center is indicated as at 18 in Figures 3 and 8. In this way more pad body is provided where the greatest wear occurs and the piling of the steel wool along the center to form a thickened portion in the pad 15 lengthwise thereof prevents high and low spots and maintains the pad at equal thickness, and permits the alternate use of opposite sides of the pad for even wear. After the wrapping as at 18, the mass is compressed from the outline position 20 in Figure 8 to the full line indication.

Thus is provided three pads, a center pad 17 (Figures 3 and 8) and two outer pads 12 and 13 (Figures 1, 2 and 9). The center pad is then placed between the outer pads 12 and 13 and the 25 whole assembly placed under a pressure sufficient to unite the three pads in unitary construction. The pressure employed in compressing the center pad 17 alone may be 200 pounds per square inch and the pressure used in compressing all three 30 pads 12, 13 and 17 to complete the operation may be 150 pounds per square inch. These working pressures are indicative of what can be used to make the pad properly, but they can and are varied for pad constructions for use in different 35 industries and can accordingly be varied as desired.

After the pad is completed, it may be placed in a fabric covering. When the three pads are combined and before pressure may be again applied thereto, the unit is wrapped about with strands 18A of the steel wool as illustrated in Figure 4. The die that is employed in the compression pinches the edges of the pads and provides smooth edges and smooth surfaces to the 45 pad which is usually enclosed as noted in any suitable envelope.

My invention is not to be restricted to the precise order of process as set forth since various changes and alterations therein may be made 50 without departing from the scope of the invention or sacrificing the advantages derived from its use.

What I claim is:

1. The method of making a pressing pad consisting in laying separate masses of steel wool in pad shape, with the strands of the steel wool extending longitudinally of the pad, compressing the 5 masses to form individual crown pads, laying another mass of steel wool in pad shape with the strands of the steel wool extending widthwise and compressing the same to form a center pad, interposing the center pad between the crown pads and then subjecting the three pads to pressure to form 10 a unitary structure.

2. The method of making a pressing pad consisting in laying separate masses of steel wool in pad shape with the strands of the wool extending 15 lengthwise of the pad and compressing the masses to form two separate identical outer pads, laying another mass of steel wool with the strands of the wool extending longitudinally and laterally of the 20 mass the longitudinal strands being greater in number about the central portion of the pad to provide a median section of increased thickness and compressing the mass to form a center pad, then interposing the said center pad between the outer pads and subjecting all of them to pressure 25 to form a unitary structure and then enclosing the pad in a fabric covering.

3. The method of making a pressing pad consisting in laying separate masses of steel wool in pad shape with the strands of steel wool extending 30 widthwise, compressing the masses to form separate pads, laying another mass of steel wool to form a central pad with strands thereof extending longitudinally and laterally and compressing said latter mass to form a pad and then 35 combining all the pads and subjecting them to pressure.

4. The method of making a pressing pad consisting in laying separate masses of steel wool in pad form with the strands of wood extending 40 widthwise, compressing the masses to form separate pads, laying another mass of steel wool to form a central pad with strands extending widthwise and longitudinally of the pad with the longitudinal strands arranged to increase the thickness of the pad along the center thereof and compressing said latter mass and then combining all 45 the pads and subjecting them to pressure to unite them in a single multi-layer pad.

C. JOHN CRARY.
